UNITED STATES PATENT OFFICE.

WILLIAM P. HAMMOND, OF PASSAIC, AND THEODORE A. HAMMOND, OF RUTHERFORD,
NEW JERSEY.

PRESSURE GAUGE.

Original application filed April 29, 1910, Serial No. 558,413. Divided and this application filed October 30, 1915. Serial No. 58,887.

To all whom it may concern:

Be it known that we, WILLIAM P. HAMMOND and THEODORE A. HAMMOND, citizens of the United States of America, residing in 5 Passaic, in the county of Passaic and State New Jersey, and Rutherford, Bergen County, New Jersey, respectively, have invented certain new and useful Improvements in Pressure Gauges, of which the following is a specification.

This is a divisional application, the subject-matter thereof having been divided out of our prior application Serial No. 558,413, filed April 29, 1910.

15 The invention relates to certain new and useful improvements in the construction of pressure gauges such as are commonly employed for measuring the pressure within a pneumatic tire or other fluid pressure container, the object of the invention being to provide a device of this character which embodies novel features of construction whereby it can be used either in connection with tire inflation means or independently 20 thereof as a pressure gauge.

Further objects of the invention are to provide a device of this character which can be set to blow-off and relieve the pressure at any desired point so as to prevent over-inflation, which can be readily applied to an ordinary tire valve casing, and which is comparatively simple and inexpensive in its construction.

With these and other objects in view, the 35 invention consists in certain novel combinations and arrangements of the parts as will more fully appear as the description proceeds, the novel features thereof being pointed out in the appended claims.

40 For a full understanding of the invention, reference is to be had to the following description and accompanying drawings, in which:—

Figure 1 is a longitudinal sectional view 45 through a blow-off pressure gauge and pump connection constructed in accordance with the invention, and

50 Figure 2 is a side elevation of the same, a portion of the blow-off jacket being broken away to show the graduated scale of the gauge.

55 Figure 3 is a detail view, partly in section, of the pump connection A.

Corresponding and like parts are referred

to in the following description and indicated 55 in all the views of the drawings by the same reference characters.

Specifically describing the construction of the blow-off gauge as illustrated by the drawings, the numeral 1 designates a tube 60 which is provided at the outer end thereof with a pressure head 2, and at the inner end thereof with an exteriorly threaded nipple 3 of such a size as to be readily screwed into the mouth of a standard tire valve casting. Surrounding the tube 1 is a barrel 4 which is adapted to slide in and out, the interior of the barrel being engaged by the pressure head 2 and the outer end of the barrel being closed by a head 5 which cooperates with the pressure head 2 and barrel 4 to provide a pressure chamber 6. The inner end of the barrel 4 has a ring 7 applied thereto and a coil spring 8 which surrounds the exterior of the tube 1 is interposed between the ring 7 and the pressure head 2 so as to normally hold the barrel 4 at the inner limit of its movement with the head 5 in close proximity to the pressure head 2.

70 The head 5 at the outer end of the barrel 4 is provided with an outwardly projecting pump engaging nipple 9 and also with an inwardly projecting inflation tube 10 which slides within the tube 1 and has an inwardly opening check valve 11 fitted 75 therein. This check valve 11 is adapted to open inwardly to permit an influx of air from a pump or the like, although it automatically closes to prevent any reflux of the air. The exterior diameter of the inflation 80 tube 10 is materially less than the interior diameter of the tube 1 so that an air passage is provided between the two members through which air can flow freely into the pressure chamber 6.

85 An exterior shell 12 surrounds the barrel 4 and is carried by the tube 1, one end of the shell 12 being formed with an end piece 13 which engages the said tube. A longitudinal slot 14 is formed in this shell 12 and a series of graduations 15 are located upon the shell adjacent the edges of the slot so as to cooperate with an annular graduation 16 on the barrel 4. It will be obvious that pressure within the pressure chamber 6 will act 100 upon the pressure head 2 to slide the barrel 4 outwardly upon the tube 1 against the action of the spring 8, and the graduations 15

are so arranged as to cooperate with the graduation 16 of the barrel to indicate the degree of pressure within the pressure chamber in pounds per square inch or other suitable measure of pressure.

When the device is used independently as a gauge, the nipple 3 of the pressure tube 1 is applied to the valve casing of pneumatic tire or like container. Extending transversely across the mouth of the nipple 3 is a rigid pin 17 which will engage and automatically unseat the tire valve in the act of applying the nipple to the tire valve casing. The pressure within the tire will be transmitted through the tube 1 to the pressure chamber 6 so as to slide the barrel 4 outwardly until the degree of pressure within the tire is indicated upon the scale 15, the pressure within the chamber 6 being then exactly counter-balanced by the spring 8. Should it be desired to increase the pressure within the tire, a pump could be connected to the pump engaging nipple 9, the check valve 11 opening inwardly to permit the influx of air and closing outwardly to prevent any reflux of air. The long inflation tube 10 projecting through the tube 1 would then serve to prevent the pulsations of pressure from the pump being transmitted to the pressure chamber 6, the pressure within the latter chamber being the "still pressure" of the tire.

The pressure gauge as thus described comprises essentially a pair of telescoping elements which are constructed for cooperation with each other to form a pressure chamber, one of the telescoping elements being provided with a seat or nipple adapted to engage the air valve casing of a pneumatic tire to place the pressure chamber in communication with the interior of the tire. One of these telescoping elements consists of the tubular member 1 and pressure head 2, while the opposite telescoping element consists of the barrel 4 and head 5. The fixed member 17 upon the nipple or seat 3 would automatically open the valve when the gauge was applied to the valve casing of a tire, and the pressure within the chamber formed by the telescoping elements would tend to move one of the said elements in such a manner as to indicate the amount of the pressure.

A blow-off jacket 18 may be fitted adjustably upon the outer shell 12 so as to automatically open the valve 11 and relieve the pressure within the tire when the pressure reaches a predetermined point. The end 19 of the jacket 18 is formed with a blow-off opening 20 which communicates with the outer atmosphere and is provided with a pin 22 adapted to engage the stem of the valve 11 to open the same when the desired pressure has been built up within the tire. This pin 22 is preferably threaded so as to be susceptible of adjustment, a lock nut 23 being provided for holding the pin in an adjusted

position. The blow-off jacket 18 is provided with a longitudinal slot 24 which loosely receives a threaded stud 25 projecting from the shell 12. A clamping nut 26 upon the threaded stud 25 serves to clamp the blow-off jacket in position, although it can be moved freely in and out upon the shell 12 when the clamping nut is loosened. The jacket 18 is of such a length that the end 26 thereof co-operates with the scale 15 to indicate the pressure which must be reached before the blow-off valve 11 will be opened by engagement with the pin 22. For instance, should it be desired to retain an eighty pound pressure within the tire, the jacket 18 would be set in position with the edge 26 thereof over the 80 graduation of the scale 15. The parts are then so arranged that as soon as the pressure within the tire is built up to eight pounds per square inch and the graduation 16 of the barrel 4 brought opposite the graduation 80 of the scale 15 the stem of the blow-off valve 11 contacts with the blow-off pin 22. Any additional pressure will now result in opening the blow-off valve 11 so as to relieve the same, although this valve will again close as soon as the pressure has been reduced to eighty pounds.

It is also contemplated to use the blow-off gauge in combination with a pump connection A. This pump connection includes a tubular body 27 and an angular branch 28 which intersects the body portion 27 and is adapted to have the blow-off gauge connected thereto. One end of the tubular body portion 27 is threaded at 29 for connection with a pump or the like and provided with an inwardly opening check valve 30, while the opposite end thereof is provided with a nipple 31 and connecting nut 32 for engagement with the tire valve casing. A cross bar 33 extends across the nipple 31 to engage the tire valve and automatically open the same when the connection is applied to the tire valve casing. The gauge can be set to blow-off and relieve the pressure when a predetermined pressure is built up within the tire, and the pump then operated to inflate the tire in the usual manner. An over-inflation is thus prevented, and the operator is warned by the sound of escaping air that the desired pressure has been reached.

In connection with the construction of the gauge, it may be mentioned that a knurled washer member 34 is fitted upon the end of the tubular member 1 to provide a finger piece which can be conveniently gripped when screwing the nipple 3 into or out of position. Set screws 35 are provided for locking this washer member 34 rigidly with the tubular member 1.

Having thus described the invention, what we claim as new and desire to secure by Letters Patent, is:—

1. A pressure gauge including a pair of

telescoping elements constructed for cooperation with each other to form a pressure chamber adapted to be placed in communication with the interior of the tire, yielding 5 means resisting the telescoping action of the elements caused by pressure within the chamber formed thereby, a nipple upon one of the telescoping elements for engagement with the valve casing of the tire, an inwardly 10 opening check valve mounted upon the opposite telescoping element and adapted to place the pressure chamber in communication with the outer atmosphere, a jacket carried by the first mentioned telescoping element and adjustable with respect thereto, 15 and an abutment upon the jacket for engaging and opening the check valve to release the pressure when a predetermined pressure is reached.

2. A device of the character described, comprising a pump-engaging means, a tire-valve-casing engaging means, a passage between said means, and a blow-off means ex-

posed to pressure in said passage, said blow-off means comprising a fixed piston, a long tube 25 on which said piston is fixed forming a second passage communicating with said first named passage, a cylinder slidable relatively to said piston, a tube attached to said cylinder extending into said first-mentioned tube and forming a restricted passage through said first-mentioned tube, whereby 30 said blow-off means is substantially responsive to the "still pressure" in the tire and is relatively unaffected by the impulses due to the action of the pump, said tube which is attached to the cylinder having a vent valve 35 therein.

In witness whereof, we have hereunto signed our names in the presence of a subscribing witness.

WILLIAM P. HAMMOND.
THEODORE A. HAMMOND.
